No. 869,020.

PATENTED OCT. 22, 1907.

C. T. RIDGELY.
TRIMMER BOARD.
APPLICATION FILED JULY 16, 1906.

UNITED STATES PATENT OFFICE.

CHARLES T. RIDGELY, OF SPRINGFIELD, OHIO, ASSIGNOR TO THE STANDARD TRIMMER COMPANY, OF SPRINGFIELD, OHIO, A CORPORATION OF OHIO.

TRIMMER-BOARD.

No. 869,020.

Specification of Letters Patent.

Patented Oct. 22, 1907.

Application filed July 16, 1906. Serial No. 326,378.

To all whom it may concern:

Be it known that I, CHARLES T. RIDGELY, a citizen of the United States, residing at Springfield, in the county of Clark and State of Ohio, have invented certain new and useful Improvements in Trimmer-Boards, of which the following is a specification, reference being had therein to the accompanying drawings.

My invention relates to trimmer boards, and more particularly to that class of trimmer boards which carry a spirit-level for adjusting the position of the board, and has for its object the production of such a board which will be cheap and durable and in which the spirit-level may be mounted in the manner allowing its ready adjustment to any desired angle.

With these objects in view my invention consists in the construction hereinafter described and more particularly pointed out in the claims.

Referring to the accompanying drawings, Figure 1 is a plan view of a portion of a trimmer board having the spirit-level secured thereto; Fig. 2 is a vertical section of the same on the line xx ; and Fig. 3 is a detail view of the fastening means for the spirit-level.

In carrying out my invention I employ a trimmer board or straight-edge 1, of any suitable type, that preferred being the form shown in the drawings, in which the trimmer board consists of an aluminium casting having its edges dressed to form straight edges and a guide groove 2 cut in the surface thereof to receive the guide member of a cutting tool.

In order that the board may be as light as possible I prefer to cast it in the form of a shell having downwardly extending flanges 3 and a thin face portion 4. Secured to the under side of this shell and preferably cast integral therewith is a recess 5 in the form of a quadrant and provided along the arc thereof with a scale 6. In the corner of this quadrant opposite the scale is a lug 7 having a screw threaded aperture 8 adapted to receive the screw 9. A spirit-level 10 having a recess 11 in one end thereof is mounted on the screw 9 and held against movement by a coiled spring 12 contained within the recess 11 and surrounding the stem of the screw 9. The opposite end of the level is preferably formed with a slot or recess 13 and adapted to engage the scale member 6 which I prefer to construct of a thin

metal plate supported at its opposite ends on the lugs 14 and forming a guide for the free end of the spirit-level 10. Extending through the walls of the recess 5 near the supporting lugs for the scale member are adjusting screws 15 which are adapted to be screwed in and out of

the recess in such a manner as to maintain the level 10

in a true horizontal or vertical position, as the case may be. That side of the recess 5 extending across the straight-edge 1 is provided with a cut-away portion or recess 16 immediately adjacent to the sight opening in the spirit-level when the same is moved to the 90 degree mark on the scale and permits the sight opening to be easily seen.

With the construction herein described it will be seen that I have provided a spirit-level which is embodied in the straight-edge itself and which may be moved to adjust the straight-edge in any position from zero to 90 degrees, the spirit-level being held in the adjusted position by the coiled spring 12 bearing against the head of the screw 9 and the bottom of the recess 11 in the said spirit-level, and that the same may be readily maintained in a true position by means of the adjusting screws 15.

While I have described my invention in detail, I wish it to be understood that the same is not limited to the details of construction which may be varied without departing from the principle of my invention.

Having thus fully described my invention, what I claim as new and desire to secure by Letters Patent, is:—

1. In a device of the character described, the combination, with a trimmer board having a depression therein forming a quadrantal recess in one side of said trimmer board and a projection on the opposite side thereof, of a spirit-level pivoted in the right angle of said quadrantal recess, and adjusting screws extending through the straight walls of said depression on opposite sides of said spirit-level to limit the movement thereof, substantially as described.

2. In a device of the character described, the combination, with the trimmer board having a recess therein, of a spirit-level having a recess in one end thereof, a coiled spring within said recess, a screw extending through said recess and engaging said trimmer board, the head of said screw engaging said coiled spring, substantially as described.

3. In a device of the character described, the combination, with a trimmer board having a recess therein, said recess being in the form of a quadrant, and supports within said recess, of a scale plate mounted within said recess upon said supports and conforming to the arc of said quadrant, and a spirit-level pivoted at one end in the right angle of said recess and having a guide adapted to engage said scale plate.

4. In a device of the character described, the combination, with the trimmer board having a recess therein, said recess being in the form of a quadrant, a spirit-level pivoted at one end in the right angle of said recess, a scale plate secured along the arc of said recess, and a recess in the free end of said spirit-level adapted to engage said scale, substantially as described.

5. In a device of the character described, the combination, with the trimmer board having a recess therein, said recess being in the form of a quadrant, of lugs in the corners of said recess, a spirit-level having a recess in one end thereof, a coiled spring within said recess, a screw extending through said recess and said spring and engaging one of said lugs, a scale plate conforming to the arc of said recess and secured at its opposite ends to the lugs at the ends of said arc, and a recess in the free end of said

spirit-level adapted to engage said scale plate, substantially as described. 10

In testimony whereof, I affix my signature in presence of two witnesses.

CHARLES T. RIDGELY.

Witnesses:

F. M. HAGAN,
EDWARD L. REED.
